UNITED STATES PATENT OFFICE.

JOHN ARTHUR YEADON AND ROBERT MIDDLETON, OF LEEDS, COUNTY OF YORK, ENGLAND, ASSIGNEES TO SAID ROBERT MIDDLETON.

PEAT-MACHINE.

SPECIFICATION forming part of Letters Patent No. 392,770, dated November 13, 1888.

Application filed January 17, 1887. Serial No. 224,650. (No model.) Patented in England March 26, 1884, No. 5,473, October 30, 1885, Nos. 13,064 and 13,067, March 4, 1886, No. 3,057, and March 13, 1886, No. 3,581.

To all whom it may concern:

Be it known that we, JOHN ARTHUR YEADON and ROBERT MIDDLETON, subjects of the Queen of Great Britain and Ireland, and residing, JOHN ARTHUR YEADON, at Albion Place, Leeds, in the county of York, England, and ROBERT MIDDLETON, at Sheepscar Foundry, Leeds, aforesaid, have invented certain new and useful improvements in machinery for forming blocks or briquettes of fuel or materials for smelting or for analogous purposes, (for which ROBERT MIDDLETON has obtained a patent in Great Britain, No. 5,473, dated March 26, 1884, and for which we have 15 jointly obtained patents in Great Britain, Nos. 13,064 and 13,067, dated October 30, 1885, and have made applications, No. 3,057, on the 4th March, 1886, and No. 3,581, on the 13th March, 1886,) of which the following is a specification.

20 The object of our invention is to provide machinery for manufacturing economically blocks or briquettes of materials for fuel or for smelting or other purposes, which blocks or briquettes are coherent and not liable to be readily broken and wasted; and our invention affords a ready 25 means of utilizing small coal or coke or small particles of other combustible materials, and small or dust-like ores, fluxes, or kindred substances which might be more or less unsuitable for use in that state by forming them into blocks or briquettes, as hereinafter described. Cohesive material must be used in combination with the materials to be formed into blocks or briquettes, unless the materials employed or some of them possess a binding 30 quality.

35 In order to properly explain our invention, we have annexed hereto drawings, with reference to which we will explain our invention.

40 The same letters refer to the same parts throughout the whole of the drawings, and the arrows denote the directions of movement of the revolving parts.

Figure I of the accompanying drawings is 45 a front end elevation of a machine constructed according to our invention. Fig. II is a plan; Fig. III, a longitudinal section through the charging-ram, and Fig. III^A is a corresponding end view of the crank and slotted lever for giving motion to this ram which charges the

molds with material. Fig. IV is a side elevation of the mechanism for compressing the material in the molds, and Fig. IV^A is an end view showing the construction of the compound lever for operating the dies. Fig. V is 55 a side elevation of the mechanism for expelling the finished blocks from the mold-plate, and also of the mechanism for imparting an intermittent motion thereto. Fig. V^A is a corresponding end view of the cams and their lever 60 for effecting the expulsion of the blocks from the molds. Fig. V^B is a perspective view of a finished block. Fig. V^C is a sectional view of one of the pressing-dies, and Fig. VI is a view illustrating diagrammatically the various motions of the machine.

A supply of the materials to be formed into blocks or briquettes (mixed with the proper proportions of pitch or other binding substance, if needed) is fed into the vertical heater 70 A, Fig. I, the position of which is shown in broken lines in Fig. II.

In the heater A, which is heated by any convenient means and has a vertical shaft (carrying knives and mixers) driven by any suitable 75 overhead shafting, the ingredients are thoroughly mixed and heated to a point at which the pitch or other binding substance (if such be used) best and most economically intermixes with the materials. From A the hot 80 material is led through a door at the foot (which may be adjusted as desired) into a spout, A', and from thence into the pug-mill B.

The pug-mill and charging-box B (whose shaft is worked by any suitable overhead gearing) has a double duty to perform. First, it has to deal with the mixture cooled down to a condition suitable for molding and to keep it in that condition, and, secondly, it has to charge the mixture into each successive mold 90 in the revolving vertical mold-plate D. The vertical shaft of the pug-mill B is provided with agitators and knives b, Fig. III, to keep the mixture in condition suitable for molding.

Fig. III shows the action of the charging-ram 95 C, which, by means of a crank-pin, C, of the shaft N, working in a slotted link, C², has a quick-return motion. The connection between the link and the charging-ram is fitted with a yielding spring, C¹. If any obstruc-

tion occurs the spring yields and the rod C^3 simply works forward through the swiveling-pin C^6 into the interior of the ram and no damage is done. By means of the nuts C^7 near 5 the link C^8 additional compression can be put on the spring, if required. The lowest knife, b , is arranged to keep the material well filled into the ram-box B' . The revolutions of the shaft N and the movements of the revolving 10 mold-plate D (which is shown with eight molds) are geared so that each forward movement of the charging-ram C' fills the mold then in position and presses the material thereinto with the degree of force arranged by the 15 strength and adjustment of the spring C^4 .

D^3 is a plate for receiving the thrust of and stopping the newly-charged material. In case the material, while passing from the heater A to the pug-mill B , does not become sufficiently 20 cool, we direct a blast of cold air into the spout A' from a fan or other available source.

Following the material now charged into the mold-plate, (see Fig. I,) it will be seen that four successive movements of this plate (see 25 arrow) (during which time further cooling is going on) will bring it in line with and ready to be acted upon by the double pressing and cupping motion. From Fig. IV it will be seen that the shaft N , (the same that drives the 30 charging-ram C'), rotating in the direction shown by the arrow, has a crank-pin fixed into an inner spur-plate wheel, M^3 . This crank-pin is connected to the tail end of the compound double-acting pendulum-lever F 35 through the medium of the yielding connecting-rod E , which is provided with spiral springs E^3 , interposed between the two parts of the connecting-rod and adjusting-nuts E^2 to permit of the adjustment of the tension of the 40 springs and of the length of the connecting-rod. This compound double-acting lever pivots in the bearing F' , across which it spans and by means of the two crank-pins or their equivalents and their adjustable rods F^2 and F^3 , which 45 may have further yielding springs, if desired, engages with the upper ends of the two pressing-ram levers G and G' . These levers have their respective fulcrum at their feet G^2 and G^3 , and a little higher up they engage with the 50 two pressing-rams which terminate in the cupping-dies H and H' . These rams, which work through and are prevented from twisting out of line by their respective guide-blocks H^2 and H^3 , have short links H^4 and H^5 , attaching them 55 to the pressing-ram levers G and G' , by which they are drawn back after each inward stroke. The action of this arrangement will now be easily understood. As the crank-pin revolves round N a rocking motion is given to the compound pendulum-lever F , which in turn draws and repels the two pressing-ram levers G and G' and their dies H and H' . The object of the long yielding springs E^3 in the connecting-rod is to allow a sufficient amount of play if a mis- 60 hap occurs. They also allow the pressure on the blocks to be regulated, as desired. The

dies H H' enter the mold-plate simultaneously and may be made to give the requisite nip by the adjusting-rods F^2 and F^3 . An advantage arises in practice from simultaneous double 70 pressing (owing probably to the friction of the pressed material against the sides of the molds) in that a harder surface is obtained on the blocks, which is a very material benefit, and such double pressing is found to be essential 75 to the proper making of blocks according to our invention. At the point where the dies H H' enter the mold-plate and the pressing commences the connecting-rod E is in the best 80 position for transmitting the pull to the pendulum-lever F , as shown on the drawings, and another advantage in this arrangement is that the slowest motion is transmitted by the crank-pin during the whole time in which the briquette is under pressure, thus giving time for 85 air to escape therefrom.

The effect of spanning the bearing F' with the compound double-acting pendulum-lever F is a great improvement in distributing the strain to the two pressing ram-levers without 90 putting any undue work on the shaft F' .

The face of each die is cupped, and as the corners of the molds in the mold-plate are similarly curved the result of the double cupping and double pressing is a well-pressed solid 95 block or briquette of the shape shown in perspective in Fig. V^c. Other shapes, even spheres, may be thus made.

Although with this machine a superior square-cornered briquette may be made, yet 100 we look upon the shape of these rounded blocks as a very great improvement, as not only are they better to handle, but in such handling and in transit they are not liable to readily break, and there is practically no waste. Although 105 we show the corners rounded, a modification might be made by beveling them off; but we prefer the rounded edges. Fig. V^c shows holes which may be drilled in the cupping-die to allow air or vapor to escape from the material 110 when it is under pressure. For clearing-out purposes these holes are of a larger diameter at the parts away from the pressing-face. Reverting to the briquette in course of formation, and which we have followed round in 115 the revolving mold-plate as far as the double pressing and cupping dies, two more movements of the vertical mold-plate bring it to the top position opposite to the expelling-gear and level with the receiving-plate. Fig. V is 120 a side elevation of this motion and shows the expelled briquette resting on the receiving-table K' and the expelling-ram K^2 drawn back out of the way, it having completed its backstroke. D is the vertical mold-plate turning on its bearings D^3 and D^4 . The peculiarity of this expelling motion is that it is worked by two cams, K^3 and K^4 , arranged side by side on the shaft N , having a strap, K^5 K^6 , encircling the shaft and the cam K^3 through its entire range, but leaving the other cam, K^4 , free 125 to revolve in the upper part of its path. The

lower member, K⁶, however, of the strap projects sufficiently to cause the cam K⁴ to act upon it during the lower part of its motion, so as to effect the withdrawal of the expelling-
5 ram K².

Fig. V^A is a cross-sectional elevation of the cams K³ and K⁴ and the strap K⁵ K⁶, and shows the lower member of the strap K⁶ projecting under the cam K⁴.

10 It will thus be seen how by this arrangement the briquette can be expelled and the ram brought back with a positive motion without the use of springs or their equivalent and then allowed to remain at rest until again 15 acted upon by the cam K³. The expelling-ram is guided at K⁷ and is connected by a rod, K⁸, to the bell-crank lever K⁹, which is incorporated with the cam-strap K⁵ K⁶ and having its fulcrum at K¹⁰.

20 The machine may be driven from any suitable prime-mover by a strap passing around the pulley M', mounted on the fly-wheel shaft M, Fig. II, at the farther end of which is a disk M², to which the fly-wheel M', (which is 25 not keyed to the shaft,) is bolted tightly up by means of a bolt, L, preferably of copper, a collar being provided on the off side of the fly-wheel to maintain it on the shaft should the bolt L shear, in which case the fly-wheel 30 will run its energy away without causing any damage. The size or strength of the bolt L should be so arranged that in the event of any serious sudden stoppage the momentum of the fly-wheel will cause it to shear the bolt and 35 liberate itself, and thus prevent further damage. It will thus be seen that the full benefit of the momentum of the fly-wheel is obtained in ordinary working and that with little or no danger in case of a sudden stoppage occurring.

40 At the other end of this fly-wheel shaft M is a pinion, M¹, gearing into an inner spur-plate wheel, M², mounted on the before-mentioned shaft N. An eccentric, N', on this latter shaft, acting through a bell-crank lever, N², Fig. V, 45 mounted on the shaft F' of the compound pendulum-lever F, actuates a pawl-and-ratchet wheel, N³, mounted on the shaft of the vertical mold-plate D and gives the requisite rotatory movement to the latter. On this second 50 motion shaft N, Fig. II, and next to the eccentric N' is the double-cam arrangement, hereinbefore described, for the expelling motion, and next to this is the overhung crank-plate C³ with its pin, which actuates the charg- 55 ing-ram. Beyond this again is another crank, o, engaged by the same crank-pin, and at the extremity of its shaft is a tappet, O', which, as it revolves, depresses one end of a lever, O², which has its fulcrum at O³ and engages at its 60 opposite end one arm, O⁴, of a bell-crank lever, which may be held down by a weight. The other arm, O⁵, of this bell-crank lever engages a sliding stop, O⁶, which enters, when released by the tappet O', one of a series of indentations provided in the periphery of the revolving mold-plate. The weight on the arm O⁴

serves the double purpose of keeping the stop O⁶ up to its work and also the lever O² in contact with the tappet O'.

As the number of teeth in the ratchet-wheel N³ corresponds to the number of molds in the mold-plate D, so that as one revolution of the shaft N brings about the requisite movement in the mold-plate from opening to opening, it follows that all the other movements, emanating, as they do, from this shaft N, will be timed, as required. In Fig. VI diagrammatic outlines of the most important motions are laid down in their relative positions, (the positions being the same as those on the details, the 70 pressing-dies being on the point of entering the vertical mold-plate.)

75 Of course it will be understood that all the actions are going on at the same time in their proper order, and that every movement of the 80 vertical mold-plate from mold to mold is accompanied or followed by all these other actions.

85 Although we have described the motion by which the vertical mold-plate is actuated, and 90 also that by which the stop or detent for fixing it in position, we may here say that we are making no claim for anything connected with these latter motions.

95 Although, for the sake of clearness, we have described the machine as we make it—viz., with a vertical revolving mold-plate—nevertheless it will be apparent that an arrangement with a horizontal mold-plate might be substituted.

100 We claim as our invention—

1. In a machine for manufacturing or pressing materials into blocks or briquettes, the combination of the vertical heater and pug-mill and charging-box with the vertical mold-plate 105 D and horizontal pressing-dies acting from opposite sides of the mold-plate simultaneously, substantially as described.

2. The combination of the pug-mill and charging-box with the vertical mold-plate D, 110 horizontal charging-ram, and horizontal pressing-dies acting from opposite sides of the mold-plate simultaneously, substantially as described.

3. The combination of the pug-mill and 115 charging-box with the mold-plate, charging-ram, operating-rod for the latter, and interposed yielding spring, substantially as described.

4. The combination of the pug-mill and 120 charging-box and mold-plate with the charging-ram, slotted link to which the ram is connected, a driving-shaft, and a crank-pin adapted to the link to give a quick-return motion, substantially as described.

5. The combination of the vertical heater and pug-mill and charging-box with a mold-plate, charging-ram, slotted link connected to the latter, and a shaft having a crank-pin adapted to the link to give a quick-return motion, substantially as set forth.

6. The combination of the mold-plate and

- opposite dies, ram-levers G G', a compound double-acting pendulum-lever, F, and connecting-rods F² F³, a driving-shaft, and yielding connecting-rod, substantially as described.
- 5 7. The combination of the mold-plate and opposite pressing-dies with double-pressing ram-levers G G', a compound double-acting pendulum-lever, F, and connecting-rods F² F³, all substantially as set forth.
- 10 8. The combination of the mold-plate and opposite pressing-dies with operating-levers, the driving-shaft, and yielding connecting-rod for the levers, all substantially as set forth.
9. A mold-plate for manufacturing or pressing materials into blocks or briquettes, having mold-openings with rounded or equivalent shaped corners, in combination with opposite dies cup-shaped and both entering the mold-

openings, all substantially as and for the purpose described.

10. The combination of the yielding charging-ram of a machine for manufacturing blocks or briquettes, and a driving-shaft therefor, with a wheel and a shearing-bolt, L, and connecting-shaft and link.

In testimony whereof we have signed our names to this specification in the presence of two subscribing witnesses.
